(57) **CLAIM**

The ornamental design for a pet enclosure, as shown and described.

DESCRIPTION

FIG. 1 is an isometric view of a pet enclosure;

FIG. 2 is a front view thereof;

FIG. 3 is a rear view thereof;

FIG. 4 is a left hand side view thereof, wherein a right hand side view is a mirror image of the left hand side view;

FIG. 5 is a top view thereof;

FIG. 6 is a bottom view thereof;

FIG. 7 is another isometric view thereof showing the frame without the screened confinement; and,

FIG. 8 is another isometric view of only the screened confinement portion.

The broken lines shown in the drawings illustrate the bounds of the non-claimed subject matter, are for illustration only and form no part of the claimed design.
